COMBINATION TOILET TISSUE PACKAGE

John J. Tepper, New York, N. Y.

Application February 28, 1950, Serial No. 146,695

1 Claim. (Cl. 206—47)

1

This invention relates to improvements in wrapper for household papers.

The principal objects of this invention are:

First, to provide a novel form of wrapper for toilet tissue, paper toweling and similar household paper which protects the paper during transportation and display and which is reusable in the home of the purchaser of the paper as a washing or polishing cloth.

Second, to provide a wrapper for household tissues which protects the tissue against wetting and soiling.

Third, to provide a wrapper capable of bearing any desired labeling and advertising indicia in the form of printed matter without danger of the print or ink soaking through and soiling the tissue within the wrapper.

Fourth, to provide a parchment washing or polishing cloth adapted for use as a wrapper for household tissues.

Fifth, to provide a novel packaged article for transportation, display and sale in which both the article and package are useful to the purchaser.

Other objects and advantages relating to details of my invention will be apparent from a consideration of the following description and claim.

The drawings, of which there is one sheet, illustrate a preferred form of my wrapper and a roll of toilet tissue wrapped therein.

Fig. 1 is a perspective view of a wrapped roll of tissue as it will be transported and offered for sale.

Fig. 2 is a plan view of the wrapper in flat position prior to or after use as a wrapper.

Fig. 3 is a fragmentary cross sectional view through the wrapper in exaggerated thickness illustrating the position of the printed material on the wrapper.

Heretofore it has been the practice to wrap toilet tissue, paper toweling and similar household papers in a relatively light tissue paper wrapping because of the economy of the wrapper itself and the ease with which it could be applied to the roll of paper. These tissue wrappings are relatively weak and highly subject to disintegration by water. In order to prevent the soiling of the contents of the package from the printing on these wrappers in case the package became wet, manufacturers have resorted to the use of nonwater-soluble inks. The only purpose of such wrappers is to provide a limited amount of protection to the enclosed paper and the wrappers are universally discarded when the package is opened.

2

I propose to wrap household papers in a wrapper of parchment paper to more perfectly protect the wrapped paper and to provide a wrapper which is reusable for other purposes after its removal from the household paper. As illustrated in the drawings, I have provided a wrapper sheet 1 of parchmentized paper of such a size as to completely wrap a roll of toilet tissue or other household paper to form a commercial article or package 2.

In order to eliminate or overcome the natural stiff and relatively brittle character of the parchment paper in its untreated state and to facilitate the application of the wrapper by automatic wrapping machines, I treat the parchmentized paper by applying glycerine to it in amounts approximating 25 per cent of the weight of the untreated parchment. I prefer to use a relatively light weight parchment weighing approximately 20 27 pounds for 500 sheets 24 by 36 inches in size. Other weights of paper can obviously be used and other proportions of glycerine upwardly from 10 per cent by weight are useful in softening and preventing cracking of the parchment.

25 The usual labeling and advertising indicia on the package is applied as at 3 by printing on the wrapper sheet 1. Preferably I employ an ink that is water soluble but at the same time resistant to cold or cool water. The ink is characterized by being substantially insoluble in water up to 60° or 70° F. but will readily dissolve in warm or hot water. The addition of soap or detergent to the water increases the solubility of the ink. I term such inks wash out inks, which 30 term is recognized in the ink industry as describing any ink consisting of a coloring pigment mixed in a vegetable oil base which will readily saponify.

A wrapper printed with these warm water soluble inks will be unaffected by rain or water from 40 wet vegetables, so there is no danger of the purchaser getting his or her hands or clothes smeared with ink while taking the article home. However, upon unwrapping the article, the wrapper can be dipped in a dishpan of warm or soapy water, and the printing will be easily removed. Since parchment paper has no fibers to soak up the ink, there is no staining of the wrapper, and all of the ink flows easily off of the wrapper, 45 leaving a clean, useful washing or cleaning "cloth". The parchment can be used and reused a great many times and is quickly cleaned by washing in water like any fabric cloth. In addition, the parchment wrapper affords increased 50 protection for the product, since water will not 55

soak through the wrapper and damage the enclosed tissue.

In order to improve the utility of the wrapper sheet 1 for use as a wash cloth, I provide a plurality of perforations 4 through the sheet. Thus when the sheet is immersed in water and wadded together in a squeezing or wringing motion, water entrapped in the sheet can leak out through the holes 4 without squirting from the folds around the edges of the sheet. However, the holes are 10 not absolutely essential particularly if the sheet is to be used in dry form as a polishing cloth or protective wrapping for food or other articles in the home. It should be noted that when holes are provided, they are located near the center 15 of the sheet where they will fall along the side of the wrapped roll. Thus any dirt which may work through the holes will spot only the outer layer or turn of the roll rather than the edges of several layers.

I have found that parchment paper of relatively light weight provides adequate protection for household tissues, under normal handling conditions, from the manufacturer to the user and is sufficiently inexpensive to permit its use 20 in place of the older tissue paper wrappers. Thus the purchaser of a roll or package of household paper obtains an adequately protected

article and in addition a washing or polishing cloth of substantial value.

Having thus described my invention, what I claim as new and desire to secure by Letters Patent is:

As an article of manufacture, a roll of toilet tissue enclosed in a protective covering of sheet parchmentized paper treated with glycerine to maintain the sheet in pliable condition, said sheet having a plurality of holes formed therethrough and having imperforate side portions of substantial width surrounding the perforate portion thereof.
